RAILWAY WHEEL CHECKING DEVICE

Marion W. Gieskieng and William A. Gieskieng,
Denver, Colo.

Application April 24, 1945, Serial No. 590,080

13 Claims. (Cl. 246—219)

1 This invention relates to a railway wheel checking device, and has for its principal object the provision of a simple and highly efficient mechanism which will automatically check the treads and flanges of railway car wheels as they pass along a section of the track to detect wheel defects such as broken flanges or treads, high flanges, hollow treads, etc., so that the defective wheels can be replaced before damage is done.

Other objects and advantages reside in the detail construction of the invention, which is designed for simplicity, economy, and efficiency. These will become more apparent from the following description.

In the following detailed description of the invention, reference is had to the accompanying drawings which forms a part hereof. Like numerals refer to like parts in all views of the drawings and throughout the description.

In the drawings:

Fig. 1 is a plan view of one rail of a railway track illustrating one form of the invention in place thereon, the opposite rail of the track would be similarly equipped;

Fig. 2 is an enlarged side view of a portion of the rail of Fig. 1;

Fig. 3 is a still further enlarged cross-section of the rail, taken on the line 3—3, Fig. 1;

Fig. 4 is a similar cross-section, taken on the line 4—4, Fig. 2;

Fig. 5 is a diagrammatic view illustrating the various circuits employed with the device of Fig. 1;

Fig. 6 is a plan view of one rail of a railway track, illustrating an alternate form of the invention in place thereon;

Fig. 7 is an enlarged side view of a portion of the rail of Fig. 6;

Fig. 8 is a cross-section through the rail, taken on the line 8—8, Fig. 7;

Fig. 9 is a detail section taken on the line 9—9, Fig. 8;

Fig. 10 is a similar detail section, taken on the line 10—10, Fig. 8; and

Fig. 11 is a diagrammatic view illustrating the circuits employed in the form of Fig. 6.

In the form of Figs. 1—5, a typical railway rail is indicated at 10, the tread portion of a wheel at 24, and the flange thereof at 25. A plurality of tread tilting members 11 are placed along the outside face of the rail 10, and a plurality of tilting flange members 12 are similarly placed along the inside of the rail 10.

These members preferably consist of four sections of angle-iron approximately 32 inches long

2 on each side of the rail. Similar tilting members would be similarly placed along the opposite rail of the track.

Each of the tilting members 11 and 12 terminates at each of its extremities in a pivot stud 13 welded to the member in the angle crotch thereof. These studs rest in receiving sockets in bracket members 14, which are secured to the opposite sides of the web of the rail by means of suitable attachment bolts 15. The studs may be held in place in the bracket members 14 in any desired manner, such as by means of cotter keys 16.

The upper faces of the members 11 and 12 are cut back at their extremities, as shown at 17, to allow space for the bracket members 14 and still maintain the adjacent members in closely spaced relation adjacent the rail. A projecting ear 18 is formed on or secured to the mid-portion of the vertical leg of each member 11 and 12. A threaded spring rod 19 passes through the web of the rail 10, and is clamped thereto by means of suitable clamp nuts 20. The rod 19 projects oppositely outward from the rail and through the opposite ears 18.

25 A pair of inner springs 21 surround the rod 19 between the members 11 and 12 and the web of the rail, and a pair of outer springs 22 are positioned on each rod 19 between the members 11 and 12 and terminal nuts 23 on the extremities of the rod 19. The springs 21 and 22 maintain the upper legs of the angle members 11 and 12 at a slight incline downward from the top of the rail.

30 The members 11 are positioned so that normally their inner edges are closely adjacent the outer face of the head of the rail and slightly thereabove so that the rim of the tread 24 of the wheel will depress the horizontal legs of the members and swing the vertical legs thereof outwardly.

35 The members 12 are positioned closely adjacent the inner face of the rail head at approximately one-half the normal flange depth therebelow so that when the wheel flange 25 passes therealong, it will depress the horizontal leg of the member 12 and swing the vertical leg thereof outwardly.

40 Naturally, should the rim of the tread 24 be broken away, it will allow the spring 22 of that member 11 to force the vertical leg inwardly, and similarly, a broken flange 25 will allow the vertical leg of that member 12 to swing inwardly toward the rail. A switch box 26 is supported below each of the members 11 and 12 upon suitable bracket members 25. These boxes contain 55 switches which are operated in consequence of

the swinging movement of the vertical legs of these members to operate a signal circuit such as shown in Fig. 5.

A tread switch blade 27 is mounted in those boxes below the members 11, and a flange switch blade 28 is mounted in the boxes below the members 12. The switch blades 27 and 28 are operated from the ears 18 in any desired manner so as to swing therewith and be electrically insulated therefrom.

When the blade 27 is swung outwardly with a normal wheel tread, it closes a circuit to a contact 29. Should the tread of the wheel be worn hollow, its rim will travel on a lower plane and will therefore force the blade 27 further outwardly so that it will close a circuit with a second contact 30. Should the rim of the tread be broken away, it will allow the horizontal leg of the member 11 to rise, under the influence of the spring 22. This causes the blade 27 to close a circuit with a third contact 31.

The blade 28 is connected by means of insulating spacers 32 with a second blade 33 and a third blade 34 so that all three will move in unison with the member 12. A normal flange 25 forces the blade 28 outwardly to close a circuit with a contact 35. Further outward movement, such as caused by a high flange, forces the third blade 34 to close a circuit with a contact 36.

A broken flange allows the member 12 to swing inwardly and upwardly under the influence of its spring 22 so that the blade 33 will close a circuit with a contact 37. The contacts 29 and 37 are connected together by means of a jumper wire 38, and the contacts 31 and 35 are similarly interconnected by means of a second jumper wire 39.

The contact 30 is connected to a relay solenoid, which will be herein designated the "hollow tread" relay 40, by means of a conductor 41; the third switch blade 34 is connected to a similar solenoid, herein designated the "high flange" relay 42, by means of a conductor 43; the second switch blade 33 is connected to a similar solenoid, which will be herein designated the "broken flange" relay 44, by means of a conductor 45; and the first switch blade 28 is connected to a fourth solenoid, which will be herein designated the "broken tread" relay 46, by means of a conductor 47.

The solenoids 40, 44, and 46 are in circuit with a battery 50 through a positive lead 51, and the solenoid 42 is in circuit with the battery 50 through a negative lead 52. All of the relays control self-locking armatures 48 which close control circuits 49, 53, 54, and 55 to any desired signals or indicating mechanisms.

Let us assume that a normal wheel is in place on the rail 10, as shown in Fig. 4 and as indicated in the diagram of Fig. 5. This closes the contact 29 to the jumper wire 38. The circuit of the latter, however, is open at the contact 37 so that no current flows. The contact 35 is closed by the blade 28 to the jumper wire 39, but the circuit of the latter is open at the contact 31 so that no current flows.

Let us now assume that a portion of the flange 25 is broken away. When this broken-away portion comes into position above the tilting member 12, it will swing the blades 28, 33, and 34 to the left in Fig. 5, causing the blade 33 to close the contact 37. Current can now flow from battery 50 through the negative lead 52 to the switch blade 27, the contact 29, the jumper 38, the contact 37, the blade 33, and the conductor 45 to the "broken flange" relay 44, thence returning to the battery through the positive lead 51. This closes the armature 48 of this relay, energizing the circuit 54 to any suitable indicating device or signal to give notice of the broken flange.

Should the tread of the wheel 24 be worn away so as to build up a dangerously high flange 25, the blade 34 will be forced into contact with the contact 36. This closes a circuit from the battery 50 through the positive lead 51, the contact 36, the blade 34, the conductor 43, to the "high flange" relay 42, thence to the battery through the negative lead 52. This closes the armature 48 of the circuit 53 to operate any desired "high flange" signal.

A broken-away tread allows the spring 22 to force the blade 27 toward the rail to close a circuit at the contact 31. This allows current to flow from the battery through the negative lead 52, the blade 27, the contact 31, the jumper 39, the contact 35, the blade 28, the conductor 47, to the "broken tread" relay 46, thence returning to the battery through the positive lead 51. This operates the armature 48 of this relay to close circuit 55 to give any desired "broken tread" signal.

The rim of a hollow tread forces the vertical leg of the member 11 still further from the rail 30 and causes the blade 27 to contact the contact 30. This closes a circuit from the battery 50 through the negative lead 52, the blade 27, the contact 30, the conductor 41, through the "hollow tread" relay 40, thence back to the battery 35 through the positive lead 51, operating the armature 48 of this relay to close circuit 49 to give any desired "hollow tread" signal.

In Figs. 6 to 11, inclusive, an alternate form of the invention is shown embodying the same principle of mechanical contact devices operated by the wheels controlling electrical signal circuits. In this form, a series of outside angle-irons 56 articulated by hinge links 57 are placed along the outside of the rail in a plane above the top thereof, and a similar series of inside angle-irons 58 also articulated by the links 57 are placed along the inside of the rail slightly below the top thereof.

Each outside angle-iron 56 is supported by two brackets 59 from a threaded cross-rod 60 extending through the web of the rail 10. The angle-irons 58 are similarly supported by means of two similar brackets 61 extending to the rod 60. The angle-irons are constantly urged upwardly 55 by means of compression springs 62 which rest upon spring blocks 63 on the rod 60. The spring blocks 63 are constantly urged toward the rail 10 by means of horizontal springs 64. The spring blocks 63 are positioned in vertical post members 65 having slotted openings 66 for the passage of the rod 60. Nuts 67 stop the outward movement of the spring 64, and nuts 68 stop the outward movement of the brackets 59. The nuts 67 and 68 are spaced apart to allow inward and outward movement of the brackets 59 and 61.

The normal position of the angle-irons 56 and 58 is indicated in broken line at "A" in Fig. 8. When a wheel moves between these members, however, they are forced outwardly to the solid line position of Fig. 8. Should a portion of the tread 24 of the wheel be broken away, the spring 64 will push the angle-iron 56 toward the rail 10 into the dotted line position "A". Further 70 rotation of the wheel will cause the unbroken part 75

of the tread to push the angle-iron 56 downwardly against the action of the spring 62.

The same action will take place on the opposite side of the rail, as shown in Fig. 11, should a portion of the flange 25 be broken away. Thus, whenever a break occurs between the rail and either of the members 56 or 58, that member will move first inwardly toward the rail to a position below the wheels, thence downwardly, as indicated by the inside angle-iron 58 in Fig. 11. This downward movement is employed to operate signal circuits, as illustrated diagrammatically in Fig. 11.

The circuits include a battery 69, a "broken tread" relay 70, and a "broken flange" relay 71. A switch box 72 is placed beneath each of the vertical post members 65 with a switch-operating plunger 73 extending upwardly therefrom. The switches in the boxes 72 are illustrated diagrammatically in Fig. 11, wherein a flange switch blade 74 is operated by the plunger which is positioned beneath the angle-iron 58 and a tread switch blade 75 is similarly operated by the plunger beneath the angle-iron 56. The blades 74 and 75 are arranged, when depressed, to close contacts 76 and 77, respectively. Both contacts 76 and 77 are in circuit with the battery 69. The blade 74 is connected by means of a conductor 78 with the relay 71, and the blade 75 is similarly connected by means of a conductor 79 with the relay 70. The relays control armatures 81, of the self-locking type, which in turn control a "broken tread" circuit 82 and a "broken flange" circuit 83 connected to any desired signal apparatus.

It can be readily seen that, should any of the angle-irons 58 be depressed by a broken flange, the relay 71 will be energized to close the "broken flange" circuit 83 and, similarly, should any of the angle-irons 56 be depressed, the circuit to the relay 70 will be closed to close the "broken tread" circuit 82. The angle-irons 56 and 58 are rounded inwardly toward the rails at each extremity of the series, as shown at 84, to allow the wheels to enter therebetween without depressing the angle-irons.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A railway wheel checking device for attachment to a railway rail comprising: bracket members extending oppositely outward from each side of said rail; tiltable metallic members supported between the pairs of bracket members at each side of the said rail, the metallic members on the outside of the rail being placed in the path of the tread of a wheel resting on said rail, and the metallic members on the inside of the rail being placed in the path of the flange of said

wheel so that the passage of a wheel will tilt the inner portions of said members downwardly; a vertical member on each of said metallic members extending downwardly from the axis thereof; a cross rod extending through the web of said rail and through said vertical members; spring means on said cross rod at each side of each vertical member to resiliently maintain said metallic members in their normal position; and signal means for indicating deviations of said vertical members from their vertical position.

2. A railway wheel checking device for attachment to a railway rail comprising: bracket members extending oppositely outward from each side of said rail; tiltable metallic members supported between the pairs of bracket members at each side of the said rail, the metallic members on the outside of the rail being placed in the path of the tread of a wheel resting on said rail, and the metallic members on the inside of the rail being placed in the path of the flange of said wheel so that the passage of a wheel will tilt the inner portions of said members downwardly; a vertical member on each of said metallic members extending downwardly from the axis thereof; a cross rod extending through the web of said rail and through said vertical members; spring means on said cross rod at each side of each vertical member to resiliently maintain said metallic members in their normal position; switch blades operable in consequence of the movements of said vertical member; and circuits controlled by said switch blades to give indications at predetermined positions of metallic members.

3. A railway wheel checking device for attachment to a railway rail comprising: bracket members extending oppositely outward from each side of said rail; tiltable metallic members supported between the pairs of bracket members at each side of the said rail, the metallic members on the outside of the rail being placed in the path of the tread of a wheel resting on said rail, and the metallic members on the inside of the rail being placed in the path of the flange of said wheel so that the passage of a wheel will tilt the inner portions of said members downwardly; a vertical member on each of said metallic members extending downwardly from the axis thereof; a cross rod extending through the web of said rail and through said vertical members; spring means on said cross rod at each side of each vertical member to resiliently maintain said metallic members in their normal position; switch blades operable in consequence of the movements of said vertical member; a contact positioned in the path of the switch blade of the outer metallic member to be closed when said member is depressed to a pre-determined position; and a signal device operable in consequence of the closing of a circuit at said contact.
